His Attorney.

UNITED STATES PATENT OFFICE

GEORGE R. BROWN, OF BRIDGEPORT, CONNECTICUT, ASSIGNOR TO GENERAL ELECTRIC COMPANY, A CORPORATION OF NEW YORK

THERMAL CUT-OUT AND GUARD

Application filed August 29, 1927. Serial No. 216,003.

The present invention relates to electric distribution, and more especially to thermal safety devices for interrupting a circuit upon the occurrence of an excess of current 5 therein.

Thermal cut-outs ordinarily comprise a block or receptacle with terminals permanently intercalated in the circuit to be protected and provided with contacts for engagement with the detachable part or plug carrying the fusible element.

The object of my invention is the provision of an improved fuse plug and a guard which may be irremovably applied to an installed 15 block or receptacle of standard construction and serve to protect the contacts thereof from being connected by other than a properly fused plug.

A common cause of accidents and injury to 20 persons and things from electric currents is due to ignorance or malicious nullification of the function of the safety cutout by short circuiting the terminals of the block or receptacle by means of a metal disk or coin, and 25 in consequence of such practice there has arisen a wide-spread demand for means to guard against it.

One embodiment of my invention is shown 30 in the accompanying drawing, in which Fig. 1 is a vertical section of a standard cut-out receptacle and of a guard and plug installed therein; Fig. 2 is an exploded view of the plug, and Fig. 3 is a similar view of the guard.

35 The standard receptacle shown in the drawing comprises a porcelain base 1 having an integral annular wall 2 at the upper side, and in the well of which is a cylindrical contact in the form of a screw shell 3 provided with a radial terminal 4 and binding screw 5 for attachment of a line wire and an independent center contact 6 extending outwardly opposite to the terminal 4 and provided with a binding screw 7 for another wire. 40 Either wire may be the supply circuit conductor and the other the circuit to be protected by the cut-out.

50 The cut-out guard comprises a cup-shaped base 8 of insulation of a diameter to provide a slight annular space between the periphery

of its flange 9 and the inner surface of the screw-shell contact 3. A radial external shoulder 10 is provided near the base of the flange, while at the bottom of the base an annular rabbet 11 is formed and from which 55 two notches 12 extend outwardly and upwardly to the periphery of the base. An axial bore 13 extends through the disk portion 14 and two diametrically disposed key recesses 15 are formed in the upper side of the 60 disk portion 14.

A sheet steel locking ring 16 with diametrically disposed arms 17 bent upwardly at an angle therefrom and provided at their ends with backwardly directed teeth or spurs 18 65 is assembled in the rabbet 11 on the bottom of the base with the arms 17 projecting through the notches 12. A narrow screw shell 19 with two diametrically disposed holes 20 for the passage therethrough of the spurs 18 is secured to the base 8 by spinning its upper edge over the shoulder 10. A washer 21 of insulation is assembled beneath the shell 19 and a hollow rivet 22 is passed through the axial bore 13 of the base, the washer 21 and a 70 metal ring 23, and then headed or spun outwardly over the latter, thereby fixedly securing all of the parts of the guard in assembled relation. The screw shell 19 is of a size easily to engage the inner surface of the 75 receptacle screw shell 3 and the spurs 18 on account of the inclination of their arms 17 deflect inward during the screwing of the guard into the receptacle screw shell 3, but upon an attempt being made to back the 80 guard outwardly they gouge into the metal of the receptacle screw shell 3 and positively lock the guard against removal.

The guard is turned home in the receptacle by means of a key or a spanner wrench (not 85 shown) inserted in the key recesses 15, so that the spun-over end of the hollow rivet 22 makes good contact with the center contact 6 of the receptacle, while the head of the rivet provides a contact for engagement by the 90 plug when the latter is in place. It is to be noted that the arms 17 of the locking ring by engaging the side walls of the notches 12 prevent the ring from turning relative to the 95 base 8, and that by their engaging with the 100

sides of the holes 20 they prevent the screw shell 19 from turning relative to the base 8.

The plug comprises upper and lower cylindrical pieces of insulation 24 and 25. The 5 upper piece 24 has a chamber 26 closed in by a metal cap 27 of ordinary construction and at the outside bottom end it is provided with a square projection 28. A metal screw shell 29, with an inturned flange 30 at its upper 10 end has a square aperture 31 to fit over the projection 28 and an integral finger 32 bent upwardly therefrom and extending into the chamber 26 for attachment to one end of the fusible element 33 located therein, is secured 15 to the underside of the upper plug part 24 by an insulating washer 34 having a square hole 35 fitting the projection 28 and clamped thereto by the lower plug part 25 which is also provided with a square recess 36 for the 20 reception of the projection 28 and is fixedly bound to the upper plug part by a hollow rivet 37 extending axially upwardly through both plug parts 24 and 25 and headed or spun over at its upper end. The lower end 25 of the fusible element 33 is secured in good contact with the inner surface of the hollow rivet 37 by metal balls 38 forced therein.

The underside of the lower plug part 25 is recessed at 39 for the reception of the contact heads of the two hollow rivets 22 and 37 so that when the plug is screwed into the receptacle the space within the cup-shaped base 8 of the guard is fully occupied by the lower plug part 25, while between the periphery of the latter and the plug screw shell 29 there is provided an annular channel for the telescopic reception of the flange 9 of the guard base.

It is to be noted that with the guard installed in the receptacle the crown flange 9 of the former serves as an insulating barrier adjacent the inner surface of the screw shell contact 3 of the latter and the well within the flange is sufficiently large to receive therein the lower part 25 of the plug which is of sufficient size to withstand the rough usage incident to ignorance or malicious attempts to short circuit the contacts by the interposition of coins or other pieces of metal between them.

While I have shown and described herein the best embodiment of the invention known to me, I do not desire to be restricted thereto.

What I claim as new and desire to secure 55 by Letters Patent of the United States, is:

1. A guard for cut-out receptacles having standard center and screw shell contacts, comprising a cup-shaped base of insulation, a center contact extending axially there- 60 through, and means on said base whereby it may be screwed into and fixedly held within the screw shell of said receptacle.

2. A guard for cut-out receptacles having standard center and screw-shell contacts, 65 comprising a cup-shaped base of insulation,

a center contact extending axially there- 70 through, a thread on the periphery of said base to engage the said screw-shell contact of the receptacle, and locking spurs mounted on said cup-shaped base and adapted frictionally to engage said screw-shell of the receptacle upon screwing home said base therein.

3. A guard for cut-out receptacles having standard center and screw-shell contacts, 75 comprising a cup-shaped base of insulation, a center contact extending axially there- 80 through, a threaded shell secured to the periphery of said base and adapted to engage said screw-shell contact of the receptacle, and locking spurs projecting radially from said base and adapted to gouge into the metal of said screw-shell contact.

4. A guard for cut-out receptacles having center and screw-shell contacts, comprising a cup-shaped base of insulation having notches formed in the lower peripheral corner thereof, a sheet metal ring mounted on the bottom of said base and provided with bent arms disposed in said notches and having locking spurs at their outer ends, a threaded metal shell extending about the periphery of said base and provided with holes through which said bent arms project and an inturned flange mounted beneath said metal ring, an insulating washer beneath said flange, and a center contact rivet extending through said base and said washer.

5. The combination with a cup-shaped guard of insulation for cut-out receptacles having standard center and screw-shell contacts, of a fuse plug having an insulating base part adapted to fit within said cup-shaped guard, and a screw-shell contact fixed to said plug in spaced relation to said base part and adapted to make engagement with the said screw-shell contact of the receptacle outside of said guard.

6. The combination of an upper plug base part provided with an internal chamber and a polygonal projection on the bottom thereof, a lower plug base part having in its top a recess corresponding to said polygonal projection, a screw-shell contact having an in-turned flange mounted on the bottom of the upper base part and provided with a polygonal hole through which said projection extends, an insulating washer mounted between said screw-shell flange and said lower base part, and a center contact rivet extending axially through said upper and lower base parts and serving to secure the several parts in fixed relation.

In witness whereof, I have hereunto set my hand this 25th day of August, 1927.

GEORGE R. BROWN.
